UNITED STATES PATENT OFFICE

2,334,587

STARTING AND BALLASTING APPARATUS
FOR ELECTRIC DISCHARGE DEVICESThomas T. Short, Fort Wayne, Ind., assignor to
General Electric Company, a corporation of
New York

Application January 28, 1942, Serial No. 428,564

10 Claims. (Cl. 315—282)

My invention relates to apparatus for starting and ballasting electric discharge devices employed on alternating current circuits. Although my invention is applicable to the starting and controlling of discharge devices of various forms, it has been particularly devised to be used with fluorescent lamps now coming into extensive use. Such lamps comprise a transparent tubular envelope containing mercury vapor at low pressure and having the inner surface of its side walls coated with a suitable phosphor which under the influence of an electric discharge through the mercury vapor produces fluorescence. The lamp electrodes which are mounted in the ends of the envelope are filamentary in form and are coated with a suitable electron emitting material. Such a lamp requires for its starting the application of a voltage impulse considerably higher than the voltage necessary to keep the lamp in operation after it has been started. In as much as the voltage required to start such a lamp is materially less if the lamp electrodes are heated prior to the application of the starting voltage and since less injury is done to the lamp if its electrodes are preheated it has become common practice to heat the electrodes to the point of electron emission prior to the application of the starting voltage. It is also common practice to effect such preheating of the electrodes and to produce the necessary voltage across the lamp to cause it to break down by using a starting device connected across the lamp in series with the lamp electrodes which device opens the circuit after the electrodes are suitably heated.

To avoid the delay incident to the preheating of the electrodes, to avoid the cost of starting devices and to avoid the cost of the additional wiring necessitated by the installation of the starting devices, instant starting of such lamps has been effected by applying thereto a voltage sufficient to make them break down immediately even with cold electrodes. For that purpose transformers have been used having high leakage but such transformers have the disadvantage that as a result of their use the power factor of the energy drawn from the source of supply is objectionably low, for example 20 to 25%.

It is the object of my invention to provide improved apparatus by which the necessary high voltage may be obtained for starting an electric discharge device without preheating its electrodes and without producing an objectionably low power factor.

My invention will be better understood from the following description taken in connection

with the accompanying drawing and its scope will be pointed out in the appended claims.

Referring to the drawing, Fig. 1 is a circuit diagram illustrating one form of my invention; Fig. 2 is a diagram showing the voltage and flux curves obtained with my invention and Fig. 3 is a circuit diagram illustrating a modification.

In Fig. 1, the electric discharge device 1, represented as a fluorescent lamp, having electrodes 2 and 2', is shown connected to be supplied through the switch 3 from the source 4 of alternating current, such for example as a 115 volt, 60 cycle lighting circuit. For providing the necessary high voltage to cause the device 1 to start without preheating its electrodes and for providing operating ballast for the device after it has been started, I have devised the reactor-transformer 5 which will now be described. As shown in Fig. 1, it comprises a core structure built up of a series of channel shaped laminations 6 and bar laminations 7, the laminations 6 in adjacent layers being reversely arranged so as to break the joints with the bar laminations in the well understood manner. The core thus formed has the two legs 8 and 9. Intermediate said legs is a stack of bar laminations forming the magnetic shunt 10, the ends of the laminations forming the shunt being separated from the adjacent portions of the core by the non-magnetic gaps 11. The gaps are very small, hence the coupling between the primary and the secondary 15 is so small during the normal running of the device that it may be neglected and the secondary considered as a series ballast. At that time the primary will draw only a small exciting current determined by the gaps 11.

Surrounding the leg 8 is the winding 13 which, in the form shown, has the intermediate tap 14 which connects with one side of the source 4 through the switch 3, the lower end of the winding connecting directly with the other side of the source 4. Thus that part of the winding below the tap is the primary and the entire winding is a secondary. The upper end of the winding 13 connects with the electrode 2 of the device 1 through the secondary winding 15 on the leg 9, the other electrode 2' being connected directly with the source 4 as shown. In the event that the source of supply 4 has a voltage high enough to operate the device 1 without being stepped up or, conversely, if the device 1 is adapted to operate on the voltage of the source, the tap 14 may be omitted and the switch 3 may connect directly with the upper end of the winding 13. Those portions of the laminations 6 forming the leg 9

each have the narrow transverse opening 17 punched therein which openings are so arranged that when the plates are stacked in the manner described, the openings 17 will align with each other. The resulting opening through the leg 9 constitutes an air gap and the narrow remaining portions 18 of the leg at each end of the gap are adapted to saturate through the major portion of each half cycle of the applied alternating current. The leg 9 accordingly contains what is commonly termed a "bridged-gap" which is adjusted to provide the correct value of current to be taken by the device.

Referring now to Fig. 2, the voltage wave applied to the device 1 upon the closure of the control switch 3 is represented by the curve 19 which from the zero point 20 to approximately the point 21 and from approximately the point 22 to the following zero point 23 represents the voltage applied to the device by the winding 13. During these intervals the portions 18 of the leg 9 are saturated. At approximately the point 21 the portions 18 begin to desaturate whereby the flux through the leg 9 undergoes a rapid rate of change as shown by the flux curve 25 until approximately the time that the point 22 is reached when those portions 18 again saturate. As a result of this rapid rate of change of flux as it passes through zero, there is induced in the winding 15 and superposed upon the voltage wave obtained from the winding 13, the voltage peak shown at 24 which peak is sufficient to cause the device 1 to break down. After the device has started, energy will be drawn from the source at approximately the power factor of the device being reduced only by the small exciting current in the primary. With apparatus such as I have described above I have obtained a power factor of 42% which it will be noted compares favorably with the power factor of 50% commonly obtained with similar devices having circuits providing for ballasting them after being started with hot electrodes.

In the modified form of my invention illustrated by Fig. 3, the core structure is built up by stacking the F-shaped laminations 30 and the bar laminations 31 together with the rectangular laminations 32 separated from the adjacent ends of the first mentioned laminations by the non-magnetic gaps 33 whereby the laminations 32 form the magnetic shunt. This form of my invention differs only in the relative arrangement of the magnetic shunt with respect to the legs of the transformer. The leg 9 of the transformer is similar in all respects to the leg 9 of the form shown in Fig. 1 as also are the windings 13 and 15. This form of my invention moreover cooperates with the discharge device 1 in exactly the same manner as has been described above. While the discharge device 1 is shown in Fig. 1 as operated on a lagging current circuit, I may if desired cause the current to be leading by including a capacitor in circuit with the device. Thus in the modification illustrated by Fig. 3 I have shown the capacitor 34 in series with the device, the capacitance thereof being sufficient to produce a leading current in the device.

What I claim as new and desire to secure by Letters Patent of the United States, is:

1. In combination, a source of alternating current supply, an electric discharge device arranged to be energized therefrom, and means connected between said source and said device for superposing a peak on the voltage wave of

said source, said means comprising a transformer having a core providing for high magnetic leakage and having a secondary connected in series between said source and said device, that part of said core whose flux is limited to that interlinking said secondary having a portion constructed to saturate.

2. In combination, a source of alternating current supply, a transformer having a core providing for high leakage and having its primary connected to be energized from said source, and an electric discharge device connected to be supplied from said source through a secondary of said transformer, that part of said core whose flux is limited to that interlinking said secondary having a bridged air gap at which saturation occurs.

3. In combination, a source of alternating current supply, an electric discharge device, a transformer having a primary arranged to be energized from said source, and a secondary, and having a core providing a leakage flux path and a flux path interlinking said secondary, said latter flux path including a bridged air-gap, and means connecting said device and said secondary in series with said source whereby a peak is superposed on the voltage wave supplied to said device from said source and energy is drawn from the source at a higher power factor.

4. In combination, an electric discharge device, a core structure providing a closed magnetic path, primary and secondary windings interlinking said path at different parts thereof, said structure including a part providing a flux leakage path shunting said secondary winding and having that part of said path interlinked with said secondary winding providing an air gap and a saturating portion in parallel therewith and means connecting said device and said secondary winding in series across said primary.

5. In combination, an electric discharge device, a core structure having a plurality of spaced legs, a primary winding on one of said legs, a secondary winding on another of said legs, and another of said legs forming a magnetic shunt, said leg having thereon the secondary winding being provided with a bridged air-gap and means connecting said device and said secondary winding in series across said primary.

6. In combination, an electric discharge device, a core structure comprising spaced members and other spaced members connecting them, a primary winding surrounding one of said connecting members, a secondary winding surrounding another of said connecting members, and another member arranged between said first mentioned members and separated therefrom by an air-gap at each end thereof, said member surrounded by the secondary winding being provided with a bridged air-gap and means connecting said device and said secondary winding in series across said primary.

7. In combination, an electric discharge device, a core structure having a plurality of windings interlinking a magnetic circuit provided thereby, said structure including a part providing a leakage path between said windings and a part having an air gap and a saturating portion in parallel therewith, and means connecting said device and one of said windings in series across the other of said windings.

8. In combination, an electric discharge device, a transformer having a primary arranged to be supplied by a source of alternating current, a secondary, and a core, said core being constructed

to provide a leakage flux path and a flux path interlinking said secondary, said latter flux path including a bridged air gap, and means connecting said device and said secondary in a series circuit to be supplied by said source of current.

9. In combination, an electric discharge device, a transformer having a two-part winding of which one part comprises a primary arranged to be connected with a source of alternating current, a secondary winding, and a core, said core being constructed to provide a leakage flux path and a flux path interlinking said secondary, said latter flux path including a bridged air gap, and

means connecting said device, said secondary, and the other part of said two-part winding in series across said one part.

10. In combination, an electric discharge device, an electromagnetic structure including a winding connected in series with said device and a source of current supply for ballasting the device after it has started and including means energized from said source for inducing in said winding a peaking voltage during a part of each half cycle for starting the device.

THOMAS T. SHORT.
